UNITED STATES PATENT OFFICE.

MORRISE E. ROGERS, OF NORWOOD, LOUISIANA.

REMOVABLE END CRANK FOR AUTOMOBILES.

Application filed March 5, 1923. Serial No. 622,742.

To all whom it may concern:

Be it known that I, MORRISE E. ROGERS, a citizen of the United States, residing at Norwood, in the parish of East Feliciana and 5 State of Louisiana, have invented certain new and useful Improvements in Removable End Cranks for Automobiles, of which the following is a specification.

My invention relates to improvements in 10 hand cranks for automobiles, specifically of the Ford type, the primary object thereof residing in the provision of such a crank that may be applied to and as readily removed from the crank shaft extension in a 15 simple and expeditious manner.

The nature and advantages of the invention will be better understood when the following detailed description is read in connection with the accompanying drawings, 20 the invention residing in the construction, combination, and arrangement of parts as claimed.

In the drawings forming part of this application, like numerals of reference indicate 25 similar parts in the several views, and wherein:—

Figure 1 is a side elevation of the motor vehicle crank shaft extension, which forms a component part of my invention, the operating 30 handle being therefore removed and an end cap being applied in its stead.

Figure 2 is a view similar to Figure 1, the said end cap being shown in cross hand section.

35 Figure 3 is a view similar to Figures 1 and 2, but showing my removable cranking lever in position upon the end of said crank shaft extension.

Figure 4 is an end elevation of the said 40 cranking lever per se, and

Figure 5 is a perspective view of a collar member employed in conjunction with this invention.

Referring to the drawings in detail, my 45 device constitutes the provision of a shaft 5, having secured to the inner end thereof at 6 a conventional form of clutch member 7. In the practical application of my device to Ford type of automobile, the usual crank 50 shaft extension is removed from its journal A after which my shaft 5 is positioned therein, in a manner more clearly shown in Figure 3.

After being positioned within the journal 55 A, there is positioned upon the shaft 5 a collar 8, the same being circumferentially

grooved as at 9, formed at its front face with a pocket 10. Adjacent the outer end of the said shaft 5, there is positioned a cross pin 11, and encircling the said shaft 5 between 60 the cross pin 11, and the said collar 8 is a relatively strong coil spring 12, the inner end thereof engaging within the said pocket 10 of the collar for maintaining the same in face to face contact with the adjacent face 65 of the journal A as well as maintaining the said clutch member 7 normally in face to face contact with the opposite end of said journal A.

The cranking lever designated 13 is a well 70 known type, the upper end thereof being formed with a right angular extending head 14 within which is a socket 15, the front end of the said head being slotted at 16 upon diametrically opposite sides thereof for the 75 reception of the ends of the cross pin 11 of the shaft 5.

In view of the above description, it will 80 at once be apparent that the clutch member 7 upon the inner end of the shaft 5 is normally maintained out of engagement with the co-operating clutch element upon the end of the motor crank shaft through the instrumentality of the coil spring 12. Whenever 85 it is necessary to crank the engine, the cranking lever may be expeditiously placed upon the end of the shaft 5, this shaft engaging within the socket 15 of the head 14 at which time the shaft 5 may be slid inwardly of the journal A for consequently engaging the 90 clutch element 7 with the corresponding clutch element upon the end of the motor crank shaft, whereby through a turning movement of the cranking lever 13 the engine may be cranked. In Figures 1 and 2, 95 I have shown a cap 17 for the end of the shaft 5 when the cranking lever 13 is removed therefrom. This cap consists of a relatively elongated and open ended cylinder formed at spaced points thereon with spring 100 fingers 18, the ends of which are curved inwardly of the said cap for forming heads 19 which are adapted for engagement within the said circumferential groove 9 of the collar 8.

In view of the above description, it is believed by me that the advantages of a device of this character will be readily appreciated by those skilled in the art, and although I have herein shown and described 105 the preferred embodiment of my invention, it is nevertheless to be understood that minor

changes may be made therein without departing from the spirit and scope of the invention as claimed.

Having thus described my invention, what I claim as new and desire to secure by Letters Patent, is:—

In combination with a shaft journaled in a bearing, a collar loosely mounted upon the shaft and bearing at one face against the shaft bearing, spring means confined at one end upon the shaft and bearing at its opposite end against the collar to hold the same in contact with the bearing shaft, said collar being provided with a circumferentially

located annular groove, a cap adapted to receive the end portion of the shaft and the said spring means, and adapted to snugly fit about the periphery of the collar and bear at one end against the shaft bearing, and resilient arms cut and formed up from the material of the cap and disposed at spaced intervals around the cap, each of said arms having an inwardly disposed bend formed therein and in the vicinity of the free end thereof to provide heads which are frictionally received in the groove of the collar.

In testimony whereof I affix my signature.

MORRISE E. ROGERS.
